UNITED STATES PATENT OFFICE.

JOHN P. NEFF, OF EAST ORANGE, NEW JERSEY, ASSIGNOR TO AMERICAN ARCH COMPANY, OF NEW YORK, N. Y., A CORPORATION OF DELAWARE.

LOCOMOTIVE-FURNACE ARCH.

1,229,380.

Specification of Letters Patent. Patented June 12, 1917.

Application filed January 8, 1916. Serial No. 71,064.

To all whom it may concern:

Be it known that I, JOHN P. NEFF, a citizen of the United States, and a resident of East Orange, county of Essex, and State of New Jersey, have invented certain new and useful Improvements in and for Locomotive-Furnace Arches, of which the following is a specification.

My invention relates to improvements in the arches of locomotive boiler furnaces and has special reference to improvements in the marginal bricks of those arches which are chiefly supported by water-circulating arch tubes in the fire-box, and in which the marginal bricks though partly supported by the outer arch tubes of the group must find the remainder of their support upon the side sheets of the firebox.

This invention is in the nature of a modification of or improvement upon the marginal brick arrangement disclosed in the C. B. Moore Patent No. 1,160,434, granted November 16, 1915. While the arrangement shown in the Moore patent is advantageous in many cases, I find that in some cases trouble is experienced through the dislodgment of the inclined marginal bricks from the studs which support the outer ends thereof upon the side sheets. It may be that the trouble is chiefly attributable to the hanging of the socketed end of the brick upon the arch tube, and also the occasional fusing together of the upper ends of the marginal bricks and the adjacent ends of the body-forming or intermediate bricks of the arch. I find also that it is not always practicable to secure requisite stability in the Moore marginal bricks by inclining them downward against the side sheet.

The object of my invention is to so modify and improve the patented structure that the marginal bricks of the arch may be supported by side sheet studs which are substantially on a level with the inclined arch tubes, and yet be effectively held against dislodgment.

A further objection which I make to the marginal bricks shown in Patent No. 1,160,434 is that the same are not reversible, but must always be used in one position between the side sheets and the tubes. Such bricks are strongly affected by the scouring action of the fire, and it is very desirable that they shall be reversible. Therefore, a further object of my invention is to provide a

marginal brick which may be placed in either position upon its supports and which may be inverted or turned bottom side up at will.

The manner in which I attain these objects, and the nature of my invention, will be readily understood on reference to the drawings which form part of this specification, and in which:—Figure 1 is a vertical transverse section of a locomotive boiler firebox containing an arch construction embodying my invention;—Fig. 2 is a sectional view on a plane perpendicular to the inclined arch tubes;—and Fig. 3 is a flat perspective view of the several bricks upon the arch tubes. 70

In Fig. 1 of the drawings, 2 represents the lower part of the flue sheet of a locomotive boiler firebox. The side sheets, 3, 3, and the crown sheet, 4, are of familiar construction. Likewise the grate, indicated by dotted lines, and also the mud-ring and boiler shell shown are all of familiar form. In most cases the firebox will be found to contain four water-circulating arch tubes, 5, which extend from the lower part or throat 80 of the flue sheet, 2, upwardly and rearwardly, to fastenings in the rear sheet (not shown) of the firebox.

The intermediate or body-portion of the arch is, substantially, laterally coextensive 85 with the group of arch tubes, extending nearly to the vertical middle planes of the outer arch tubes. This intermediate part of the arch is composed of a plurality of longitudinal rows of refractory bricks, 6, the 90 ends of which rest upon and are supported by the arch tubes. My invention is not concerned with the details of the formation of the intermediate part of the refractory arch; beyond this, I prefer that in all cases the 95 outer edges of such intermediate or body-portion of the arch shall not extend beyond the vertical axial planes of the outer tubes, 5, 5. The reason for this is that it is desirable to prevent actual or fusing contact between the intermediate bricks and the marginal bricks about to be described. 100

Upon the inner side of each side sheet I provide a row of side sheet studs, 7. These studs, 7, are arranged, preferably, in a 105 plane, somewhat above the plane which contacts the bottoms of the tubes, 5. They are therefore directly opposite and preferably in horizontal-plane alinement with the outer tubes, 5, 5. For closing the spaces between 110

the side sheets and the outer tubes, 5, as required to prevent direct passage of the flame from the fire-chamber to the flues of the boiler, I employ a plurality of refractory bricks, *a*, of peculiar shape. The parts, 9, and, 10, of these bricks, which are presented to the side sheets and the tubes, 5, respectively, will be described as the "ends" of the brick, *a*. The faces, 11, will be referred to as the sides of the brick. Whether the remaining faces, 12 and 13, shall be described as top and bottom, respectively, depends upon the position in which the brick is placed in the firebox, for, as will presently appear, these marginal bricks are reversible.

The length of each brick is approximately determined by the distance between the side sheet and the adjacent arch tube. In many cases the side sheet substantially parallels the adjacent arch tube and in such cases all of the marginal bricks are of the same length, as represented in Fig. 3 of the drawings. In other cases an inclined side sheet is encountered, and in such cases I prefer that a series of marginal bricks shall be provided of the different lengths necessary to fit such a side sheet. But this modification of sizes usually affects the shape of the bricks only in matter of the length thereof. In other respects all of the bricks remain the same and operate on the same principle.

It will be noted that the tops and bottoms of the marginal bricks, *a*, are substantially parallel planes. The sides, 11, 11, of the bricks are likewise substantially parallel planes, preferably perpendicular to the top and bottom. Likewise the ends, 9, and 10, are preferably parallel planes, but these planes are angularly disposed to the top and bottom planes. Each end forms an acute angle, 14, with one of the planes, 12, 13, and an obtuse angle with the other. Thus each brick is provided with two inclined ends, with acute angles diagonally opposite one another; and each brick is made to present two diagonally extended portions, *a'*, and *a''*, the lower of which (*a'*) rests against the side sheet of the firebox and upon the studs, 7, while the upper extension, *a''*, overhangs the adjacent tube, 5. The angling of the outer end removes its upper part from the side sheet. The angling of the inner end of the brick present the described

overhanging extension and an angular or 55 wedging bearing upon the arch tube. As clearly shown in Fig. 2, the angle or bevel of the end upon the arch tube causes the weight of the brick, *a*, to act against the round side of the arch tube and thus a positive force is effected to constantly thrust the brick outward against the side sheet of the firebox. In this manner I positively insure the retention of the brick upon the supporting studs. Obviously, the inner end of 60 the brick cannot fall as long as any portion of that end overhangs the arch tube. In securing this advantage, I also leave the inner end of the brick free to move upon the arch tube and thus secure the advantages of 65 a marginal brick which automatically adjusts itself to changes of position between the tube and the side sheet, due to the expansion, contraction, and warping thereof. As stated, the ends of my novel marginal 70 arch bricks are reversely symmetrical and it will be obvious that the marginal bricks may be inverted at will. It should be noted that these many advantages are secured in and by a marginal brick form that is extremely 75 simple in outline and very inexpensive to manufacture, and which may be piled and transported and stored with minimum danger of breakage.

Having thus described my invention, I 80 claim as new and desire to secure by Letters Patent:—

The herein described improvement, comprising a locomotive firebox, its side sheets and inclined water-circulating arch tubes, in 90 combination with an arch body of refractory bricks supported by said arch tubes and substantially co-extensive therewith, rows of marginal-brick-supporting studs provided in said side sheets substantially 95 in the plane of said tubes, and marginal bricks, each presenting an acute angled end having its vertex against a side sheet and having a plane surface resting upon one of said studs, and each also presenting a diagonally opposite acute angled end having a plane surface upon and against the adjacent arch tube, substantially as and for the purposes described.

In testimony whereof, I have hereunto set 105 my hand this 28th day of December, 1915.

JOHN P. NEFF.
